UNITED STATES PATENT OFFICE

2,155,764

METHOD AND APPARATUS FOR SCREENING
WET MATERIALAdolph W. Lissauer, Louisville, Ky., assignor to
Louisville Drying Machinery Co., Incorporated,
Louisville, Ky., a corporation of Kentucky

Application July 30, 1936, Serial No. 93,446

9 Claims. (Cl. 210—151)

My invention relates to a method and apparatus for decreasing the liquid content of materials such as distillery slop, paper pulp, cotton linters, et cetera.

5 The principal object of this invention is to provide a more efficient method, and more enduring apparatus, for the reclamation of solids than heretofore available.

Another object is to construct the apparatus 10 at relative low cost, and to reduce materially personal supervision and service in terms of current equipment, thereby reducing maintenance costs.

The United States Patent No. 1,669,973, issued 15 to Julius Credo, discloses a type of reclaiming or screening apparatus that has been quite extensively used for reducing the liquid content of distillery slop. Although the Credo apparatus is an improvement over earlier apparatuses, long 20 use has shown that chains 15 break, permitting broken links thereof to pass on with the solids of the slop, and seriously damage other machinery.

The apparatus of the incident invention eliminates this objectionable feature, of the Credo apparatus, and is constructed so that it may readily 25 replace the chains, paddles and sprockets of existing Credo reclaimers.

In order to further warrant a replacement of the Credo reclaimers, the apparatus of the incident invention is constructed and arranged to 30 provide greater capacity and efficiency for the same size screen employed on commercial Credo reclaimers.

Thus the principal object of this invention 35 resides in the provision of rotatable stirring and distributing means that provides a transverse as well as a horizontal movement of the wet material, and which eliminates the use of the objectionable chains and sprockets.

40 A preferred embodiment of my invention is illustrated in the accompanying drawing in which

Figure 1 is a plan view of the apparatus with portions removed to reveal detailed structure.

Fig. 2 is a side elevation of Fig. 1 from which 45 the near wall has been removed to disclose structure in full lines.

Fig. 3 is a plan view of a set of paddles, sometimes referred to hereinafter as a "rotor", and one phase of the relation of material in process to 50 same.

Fig. 3A is an elevation of Fig. 3.

Figs. 4 through 10 are plans and elevations illustrating modified constructions for the rotors.

Reference characters 15—16, 17—18 and 19, 55 respectively, represent sides, ends and bottom of

a box like structure referred to hereinafter as a trough. Supported and spaced by minor and major sills 20 and 21, which are carried by side walls 17—18, are a plurality of graded perforated copper plates or other screening material 22. 5 Major sills 21 provide sub-troughs 23—24 that collect and convey separated material to outlets 25, 26. At the upper end of the trough, is a feed hopper 171 that receives wet material for treatment, while the concentrate or recovered residue 10 discharges from the lower end 18 into disposal duct 27.

Attached to the side walls of the trough, are beams 30, each of which carries a bracket 31. 15 Each bracket is fashioned with a vertical journal for a vertical shaft 32, and a pair of horizontally spaced journals 33 in which rotates a main shaft 34. Between each pair of spaced journals 33 is lodged a worm 35 keyed to the main shaft 34. To the upper end of each vertical shaft is keyed 20 a gear 36 in mesh with an associated worm 35, while, attached to the lower end of each vertical shaft is a hub 37 equipped with blades or paddles 38 for controlling and manipulating the wet material under treatment, referred to hereinafter as 25 "material". Right and left hand sets of worm gears are employed to impart clockwise and counterclockwise rotation to the vertical shafts 32, as indicated by the curved arrows in Fig. 1. It should be noted that the paddles of each successive shaft are so related that they traverse an area overlapping the area traversed by the paddles of each adjacent shaft. Mitre gears 39 and shaft 40 transmit operating power to the main shaft 34, and, as indicated by the power transmitting equipment, the paddles driven by the main shaft travel slowly.

The mounting of brackets 31, and the method of adjusting same in relation to beams 30, does 40 not constitute a part of this invention, therefore, the details are not included. However, it must be understood that means are provided to locate and maintain the paddles for rotation in a plane spaced from and parallel to screens 22, so that a substantially uniform layer or bed of material remains in contact with screen 22, for the purposes 45 adverted in the said Credo patent.

By locating the paddles, so that their bottom edges are set at a selected distance from screens 22, a filter layer or bed is maintained and allowed 50 to gravitate from the top to the bottom end of the trough in a substantially straight path, while the material above the filter layer has an entirely different course and treatment as described hereinafter.

The straight arrow, in Figures 1 and 3, indicates the gravitational path of the material as it approaches the first or top rotor, while the shaded areas 41, 42, 43 and 44, in Fig. 3, indicate the behavior of the material in response to the combined action of gravity and the rotation of the paddles. As a paddle 38 progresses in the direction indicated by an adjacent curved arrow, material 41 is gathered, slightly compressed and transferred from the near side to the far side of the trough. During this movement an additional separation over and in addition to the Credo method is procured because of the mechanical pressure applied to the material by the paddle, 15 and the greater distance of travel provided therefor. The paddle may be perforated, as indicated in Fig. 3A by numeral 381, to permit liquid to drain therethrough, and onto the established filter bed. As the paddle progresses, the material 20 will drop away, substantially as indicated by reference characters 42, 43 and 44, and be gathered by a paddle of an adjacent rotor, which similarly transfers it from the far to the near side of the trough. This process is repeated, seratim, by the 25 remaining rotors to the last one where the concentrated material gravitates into duct 27.

In Fig. 2, the elevation of the paddles represents all of the bottom edges as being in a common plane, whereas, in Fig. 5, the bottom 30 edges of adjacent blades are disposed in different planes, consequently only the opposite blades have bottom edges in the same plane.

Fig. 7 is an end elevation of a paddle of the rotor shown in Fig. 6, and is illustrated inclined 35 in the direction of rotation, with material gathered and downwardly pressed for expediting removal of the liquid content. The curved arrows in Fig. 6 indicate clockwise and counter-clockwise rotation for the rotor. In Fig. 6, all 40 paddles are indicated as being inclined in the same direction for applying pressure to the material, when rotated in the clockwise direction, or, functioning as a plow when rotated in the counter-clockwise direction. However, adjacent 45 paddles can be inclined in opposite directions, so that, in either direction of rotation, the material will be alternately compressed against the screen, and then lifted or plowed away from the screen by a succeeding paddle. It must be understood that the paddles can be made of solid 50 or perforated material, in whole or part, and adjustable as a group, or independently, for the accomplishment of objectives according to the behavior of the material to be processed. Thus, 55 the inclination for each paddle can be selected according to whether the material is to be transferred, downwardly compressed and/or plowed.

Fig. 9 is an end elevation of a paddle of the rotor shown in Fig. 8, and indicates material 60 being gathered from screen 22, on which is formed or maintained the Credo filter bed, indicated by numeral 221. The paddles of this rotor may likewise be arranged to plow, as well as compress or transfer, the material during rotation.

65 Fig. 10 illustrates a rotor equipped with paddles having curved ends, which can be rotated in either direction to retard or expedite movement of the material.

While several applications, modifications and 70 combinations have been dealt with, to disclose some of the actual uses for which the incident method and apparatus can be employed, many other variations and combinations are available to expeditiously process a wide range of materials.

Having thus described my invention, I claim:

1. In an apparatus for straining and filtering liquid containing non-liquid material the combination of an angularly disposed planar screen and a plurality of angularly disposed paddles 5 rotating in a plane spaced substantially parallel from and cooperating with said screen for manipulating said material.

2. In an apparatus for straining and filtering liquid containing non-liquid material the combination of an angularly disposed planar screen and a plurality of perforated paddles rotating in a plane spaced substantially parallel from and cooperating with said screen for manipulating said material.

3. In an apparatus for straining and filtering liquid containing non-liquid material the combination of an angularly disposed screen consisting of a perforated plate having a substantially flat face and a plurality of rotors equipped with 20 perforated paddles rotating in a plane substantially parallel to and cooperating with said screen for handling said material.

4. A filtering apparatus comprising an inclined screen over which wet material moves gravitationally; means depositing wet material on said screen at an elevated point; means distributing the deposited material over the surface of said screen to provide a thorough filtering of liquid therefrom, said distributing means comprising a 30 succession of rotating vanes each having their axis of rotation substantially perpendicular to the surface of said inclined screen and having a path of travel overlapping the path of travel of an adjacent vane, to provide a continuous distribution 35 of the said material in its gravitational movement down the said inclined screen; and means collecting the liquid filtered from said material and passing through said screen.

5. A filtering apparatus comprising an inclined 40 screen over which wet material moves gravitationally; means depositing wet material on said screen at an elevated point; a plurality of shafts positioned above, and substantially perpendicular to the surface of said inclined screen; a succession of substantially radial vanes each attached to each shaft, the vanes of each shaft having a path of travel overlapping the path of travel of the vanes of an adjacent shaft, to provide a continuous distribution of the said material over 45 the surface of the said screen in its gravitational movement down the said inclined screen; means rotating alternate shafts in one direction, and the intermediate shafts in a reverse direction, the vanes attached to each shaft pushing the 50 deposited material, in its gravitational movement down the inclined screen, horizontally into the path of travel of the vanes of an adjacent shaft, to lengthen the path of travel of said material while moving over said screen; and means collecting liquid filtered from said material and 55 passing through said screen.

6. An apparatus for filtering wet material comprising an inclined screen, means depositing wet material on said screen at an elevated point; means breaking-up the deposited material by moving the upper portion of the deposited material transversely of said screen in alternate directions to provide a thorough filtering of liquid 65 therefrom through the portion of the material remaining in contact with the surface of said screen, the latter means comprising a plurality of members rotating in a plane substantially parallel to the surface of said screen, the path of travel of each member overlapping the path of 70 75

travel of an adjacent member to provide a continuous breaking-up of the material as the said material moves down the said inclined screen; and means rotating the alternate members in one direction, and the intermediate members in a reverse direction, to provide the alternate movement of the upper portion of the material, as recited.

7. An apparatus for filtering wet material comprising an inclined screen on which the material moves gravitationally; means depositing wet material on said screen at an elevated point; means moving the deposited material in a substantially sinusoidal path over the surface of said screen to lengthen the path of travel of the deposited material thereover, said moving means comprising a plurality of shafts positioned above, and substantially perpendicular to the surface of said inclined screen; a plurality of substantially radial vanes attached to each shaft, the vanes of each shaft having a path of travel overlapping the path of travel of the vanes of an adjacent shaft; means rotating alternate shafts in one direction, and intermediate shafts in a reverse direction, whereby the vanes attached to a shaft near an elevated point of said screen pushes the deposited material, in its gravitational movement down the inclined screen, into the path of travel of the vanes

of an adjacent shaft, to provide the sinusoidal movement of the deposited material, as recited.

8. An apparatus for filtering wet material including an inclined screen; means depositing wet material on said screen at an elevated point; means continuously stirring a portion of the deposited material to provide a thorough filtering of liquid therefrom through a portion of said material remaining in contact with the surface of said screen, said stirring means comprising a succession of rotating elements, each having a path of travel extending into the path of the wet material, and overlapping the path of travel of an adjacent element.

9. An apparatus for filtering wet material including an inclined screen on which the material moves gravitationally; means depositing wet material on said screen at an elevated point; means continuously stirring the deposited material to provide a thorough filtering of liquid therefrom through said screen, said stirring means comprising a succession of rotating elements, each continuously rotating in the said material and having a path of travel overlapping the path of travel of an adjacent element to provide the continuous stirring of the wet material as recited.

ADOLPH W. LISSAUER.
